UNITED STATES PATENT OFFICE.

ROBERT WOOD, OF BROOKLYN, NEW YORK, ASSIGNOR TO THE NATHAN MANUFACTURING COMPANY, OF NEW YORK, N. Y., A CORPORATION OF NEW YORK.

LUBRICATOR.

1,192,253.

Specification of Letters Patent. Patented July 25, 1916.

Application filed November 27, 1915. Serial No. 63,703.

To all whom it may concern:

Be it known that I, ROBERT Wood, a subject of the King of Great Britain and Ireland, residing at Brooklyn, in the county of 5 Kings and State of New York, have invented certain new and useful Improvements in Lubricators, of which the following is a specification.

This invention relates to a heater for oil 10 reservoirs for locomotives and the like, and its novelty consists in the construction and adaptation of the parts, as will be more fully hereinafter pointed out.

Oil reservoirs on locomotives are 15 commonly so placed that they are exposed to the weather, and when it is cold the oil is apt to become congealed and stiff so that it is not fed properly or continually to the parts to be lubricated. Attempts have been made 20 to remedy this condition by surrounding the lubricant supply holder with a steam jacket or passing a steam pipe completely through the reservoir and the body of lubricant contained therein. But most lubricating oils 25 are compound bodies or mixtures having varying boiling points and as steam is never less than two hundred and twelve degrees Fahrenheit in temperature, and when supplied to such a reservoir under ordinary conditions of use of a locomotive, is frequently 30 of a higher temperature, some or the major portion of the lubricant employed, when subjected to such a temperature, is apt to be injuriously affected thereby if not completely 35 disintegrated.

My invention relates to a simple and novel means by which the oil can be kept at a proper temperature for use without encountering the danger above specified.

40 In the drawings, Figure 1 is a side elevation of a lubricant holding device equipped with my novel invention, a portion of the parts being shown cut away to show concealed parts and a heating device being 45 shown in vertical central longitudinal section; Fig. 2 is a transverse section on the plane of the line 2—2 in Fig. 1, and Fig. 3 is a side elevation partly diagrammatic showing the method of equipping a locomotive with the device illustrated in Figs. 1 and 2.

In the drawings, 10 is a reservoir of any 50 convenient size and shape, provided with a bottom 11, side walls 12, 12, and a top 13, 55 the latter being provided with a threaded

opening adapted to receive a cover or closing plug 14. Brackets 15, 15 project inwardly from the side walls and serve to support a strainer of usual form indicated at 16.

At a convenient place, in two of the opposite side walls of the device, are formed apertures internally threaded and adapted each to receive fittings indicated at 40 and 41 respectively and which are in line with each other and are adapted to support the other parts of the heating device presently to be described. Each of these fittings comprises a threaded nipple 42 adapted to be screwed into the side wall of the reservoir, a longitudinal annular or tubular body indicated at 43, and which is provided with one or more transverse apertures indicated at 44, 44, and a terminal threaded nipple indicated at 45.

Snugly fitting within each of these members 40 and 41 and transversely arranged across the reservoir is a pipe or tube indicated at 50, which is provided with oppositely arranged apertures 51, 51 adapted to register with the apertures 44, 44, in the fittings referred to. This pipe is closed by means of a plug 55, 55, one at each end, which is secured in place by means of couplings 56, 56 in any usual manner. The plugs 55 are each provided with a central tubular bore 57, one of which at least is threaded and both of which are adapted to receive and support a steam pipe 60 arranged transversely across the entire apparatus, and which pipe is open at both ends 75 and is adapted to communicate with the bore 57. An appreciable annular space 61 is left between the inner surface of the tube 50 and the outer surface of the pipe 60 and this space, it will be noticed, has two dead ends formed by the inward terminal spaces of the plugs 55, 55 and yet communicates with the outer air through the apertures 51, 51 in the pipe 50, and the registering apertures 44, 44 in the fittings 40 and 41.

100 Each of the plugs 55 is provided with a terminal annular flange 58 internally threaded, whereby there may be connected thereto a steam conduit 65 leading from any source of steam supply on one side of the device and a steam outlet 66 leading to a convenient discharge place on the other side of the device.

105 By means of the described device, it is evident that a current of steam may be 110

caused to pass from a source of steam supply through the pipe 60 and thus across the entire apparatus and be discharged at its opposite side. At the same time, it is evident that 5 a current of air will enter the apertures 44, 44, reach the space 61 between the steam pipe 60 and the outer pipe 50, will pass through such space, and around the pipe 60, and will be discharged at the corresponding 10 apertures 44, 44 at the other end of the apparatus. The pipe 60 it is obvious has no communication with the pipe 50, and the latter is open at both ends as described, so that it is evident that the current of air through 15 the pipe 50 will move in whichever direction the locomotive is moving.

Any means may be employed to force oil from a supply reservoir of this kind to the places to be lubricated. One such means is 20 described in Letters Patent of the United States, No. 1,162,275 issued to me November 30th, 1915, but the device which I prefer to employ is described and claimed in a pending application for Letters Patent of 25 the United States, Serial No. 63,421, filed November 26th, 1915, which device is described as follows: Secured to or made integral with one of the side walls of the reservoir 10 is a cylinder 17 open at both ends 30 and adapted to receive a pump piston 18. Also secured to or made integral with the opposite side wall of the reservoir is a cylinder 19 arranged in line with the cylinder 17, there being a clear space of substantial 35 dimensions between the two inner ends of the two cylinders. The cylinder 19 is open at both ends and is adapted to receive a barrel 20 provided with a central oil receiving tube 22 expanded at its outer end to form a 40 chamber 23 containing a valve 24. The outer end of the barrel is provided with an annular flange 25 internally threaded and adapted to receive a coupling 26 having a central bore 27, expanded at the end adjacent 45 to the chamber 23 to form an extension 28 of such chamber and adapted to receive a stem 29 of the valve 24, and a retraction spring 29* adapted to restore the valve to place after it has been unseated. A 50 nipple 30 is secured to the coupling 26 and to this nipple is connected a conduit (not shown) adapted to carry the oil to the place to be lubricated.

At the end of the pump piston 18 there is 55 provided a ram 30 fitting closely within the tube 22 and of such a length that when the piston is at the end of its stroke toward the left the ram will be wholly withdrawn from the tube. Means are provided to impart a 60 reciprocating motion to the pump piston and the ram, consisting of a supplemental housing generally indicated at 31 secured to or made integral with the reservoir casing 10 and affording a slideway for a cross head 65 32 secured to the piston and provided with

a slot 33 adapted to be engaged by a pin 34 carried by a crank 35 mounted on and moving with the shaft 36 supported in suitable bearings in the side of the housing and oscillated by means of a lever 37 and link 38 connected to any suitable reciprocating or oscillating member on the locomotive, for instance the member indicated at 39.

In using the device, the reservoir is filled with oil by pouring the same through the 75 top and allowing it to pass through the strainer 16. The reservoir should be filled with oil and kept filled above the level of the cylinders 17 and 19. When the piston is moved toward the left and the ram 30 is 80 completely withdrawn from the tube 22 the oil fills this tube and presses against the valve at the outer end thereof. When the reverse movement of the piston takes place, the ram enters the tube and forces a portion 85 of the oil past the valve and against the action of the valve spring and on into the conduit referred to. When the ram is again withdrawn from the tube a fresh portion of oil enters it and is forced forward as before. 90 The valve spring serves to retract the valve to position after it is unseated and to prevent any backward flow of the oil into the reservoir. It will thus be seen that by means of the device in question a supply of 95 oil is intermittently delivered to the parts to be lubricated through the conduits referred to.

I claim:

1. The combination with a reservoir for 100 a lubricant, of a source of steam supply, a conduit for the steam passing through the reservoir, and a conduit surrounding the steam conduit and spaced apart therefrom and without communicating therewith and which surrounding conduit communicates with the air at both ends.

2. The combination with a lubricant reservoir, of a source of steam supply, a pipe adapted to conduct the steam to and through the reservoir, and means for keeping the pipe out of contact or communication with the lubricant in the reservoir, comprising an outer inclosing pipe open at both ends to 110 the atmosphere.

3. A device of the character described, comprising an oil reservoir and means for forcing the oil therefrom through a suitable conduit to the parts to be lubricated, means for maintaining the oil in a heated condition without burning, comprising a steam pipe located within the body of oil in the reservoir and means for cooling its outer surface.

4. A device of the character described, comprising an oil reservoir and means for forcing the oil therefrom through a suitable conduit to the parts to be lubricated, means for maintaining the oil in a heated condition without burning, comprising a steam pipe located within the body of oil in the reser- 125 130 135

voir, and means for cooling its outer surface, consisting of a device adapted to cause a current of air to pass along the outside of the pipe and to be maintained in contact 5 therewith during such passage.

5. The combination with a reservoir adapted to hold a supply of lubricant, of means for heating the lubricant and at the same time preventing it from attaining an undesirable temperature, comprising a pipe 10 adapted to conduct a heating fluid to and through the reservoir, and an outer pipe surrounding the first pipe so arranged that a substantial space is provided between the 15 two pipes.

6. The combination with a reservoir adapted to hold a supply of lubricant, of means for heating the lubricant and at the same time preventing it from attaining an undesirable temperature, comprising a pipe 20 adapted to conduct a heating fluid to and through the reservoir, and an outer pipe surrounding the first pipe so arranged that a substantial space is provided between the two pipes, and means for passing a current of fluid cooler than the fluid in the first mentioned pipe through the space between the two pipes.

In testimony whereof I affix my signature.
ROBERT WOOD.
